(57) **CLAIM**

The ornamental design for a fold-up toy bed, as shown and described.

DESCRIPTION

FIG. 1 is a perspective view of a fold-up toy bed shown in accordance with our new design, in the folded up position; FIG. 2 is a front elevational view thereof, the back being a mirror image;

FIG. 3 is an end elevational view thereof, the opposite end being a mirror image;

FIG. 4 is a top plan view thereof;

FIG. 5 is a bottom plan view thereof;

FIG. 6 is a perspective view thereof in the unfolded position; FIG. 7 is a side elevational view thereof, the opposite side being a mirror image;

FIG. 8 is a front end elevational view thereof;

FIG. 9 is a back end elevational view thereof;

FIG. 10 is a top plan view thereof; and,

FIG. 11 is a bottom plan view thereof.

Throughout the figures phantom lines are for purposes of illustration only and form no part of the claimed design.
